UNITED STATES PATENT OFFICE.

ALFRED M. THOMSON, OF NEWARK, NEW JERSEY, ASSIGNOR TO JOSEPH MERCADANTE,
OF NEW YORK, N. Y.

REFRIGERATING APPARATUS.

Application filed October 20, 1926. Serial No. 142,846.

This invention relates to refrigerating apparatus, and particularly to refrigerating apparatus of the compression type. One of the objects of the invention is to provide an efficient refrigeration system having the various parts arranged in a compact form and constructed in such a manner that the parts can be readily assembled, and so that the system will require little or no attention after it is installed.

Refrigeration systems of the compression type include a refrigerating element located in a cooling chamber and supplied with a liquid refrigerant which upon changing to the gaseous state within the cooling element, produces the desired cooling effect. The system includes a pump or compressor for compressing the gasified refrigerant, a condenser for cooling and liquefying the compressed refrigerant, and an expansion valve through which the refrigerant passes to the refrigerating element. A rotary pump is suitable as a means for compressing the gasified refrigerant. Where such a pump is used, it is necessary to provide a sealing fluid for the pump. It is desirable to cool this sealing fluid in order to prevent particles thereof from being carried over into the condenser and ultimately into the refrigeration element, and one object of my invention is to provide improved means for cooling this sealing fluid.

My invention contemplates the provision of an improved casing for a rotary pump or compressor, provision being made for cooling the sealing fluid within the casing. In general, this is accomplished by providing one or more air passages extending through the casing and providing suitable means, such as a fan, for causing air to flow through the passages. I prefer to employ a condenser comprising two parts located near each side of the pump casing, the arrangement being such that a single fan can be used for the purpose of causing air to flow against the condenser and through the passages in the pump casing. A motor is provided for driving the pump, and the fan can be located on the motor shaft or so as to be driven by this shaft. The expansion valve of the system is preferably located at one side of the motor and a valve manifold for servicing the system and controlling the flow of the refrigerant can be located on the other side of the motor. The various

parts can thus be arranged in a minimum of space without rendering any of the parts inaccessible in the event that repairs are necessary.

The various objects and advantages of my invention, some of which have been mentioned above, may be best understood by considering the following detailed description, which is to be taken in conjunction with the accompanying drawings illustrating one embodiment of my invention. In the accompanying drawings,

Fig. 1 is a plan view of a refrigerating apparatus constructed in accordance with my invention;

Fig. 2 is an elevation, partly in section, of the apparatus shown in Fig. 1;

Fig. 3 is a vertical section view taken on line 3-3 of Fig. 2, showing details of construction; and

Fig. 4 is a vertical section view of a check valve forming part of the system shown in Figs. 1, 2 and 3.

In the accompanying drawings, I have illustrated a compressor or pump casing 1, enclosing a rotary pump 2 of the gear type. The pump shaft 3 is driven by a motor 4 through a flexible coupling 5. A fan 6 is mounted on the motor shaft and is adapted to produce a current of air directed against a condenser 7 and against the casing 1. A pipe 8 connects the upper part of the condenser with the interior of the casing 1 through a valve 9 carried by a closure plate 10 covering an opening in the top of this casing. The rotary pump 2 is carried by a closure plate 11 covering an opening in the side of the casing near the top thereof. A gasified refrigerant such as sulfur dioxide is supplied to the pump through a pipe 12 which communicates with the pump through the closure plate 11. The pipe 12 communicates with a valve manifold 13 which in turn communicates with a pipe 14 leading from the refrigeration element (not shown). The compressed refrigerant, after being liquefied within the condenser 7, passes through the pipe 15 to a float valve 16. After passing through this valve, the refrigerant is conducted to the refrigeration element through the pipe 17.

The gasified refrigerant returning from the refrigeration element flows through pipe 14, manifold 13, pipe 12, to the pump 2, which compresses it and discharges it into

the pump casing 1. The compressed refrigerant then passes through the pipe 8 into the condenser 7, then through pipe 15 to the expansion valve 16, and back to the refrigeration element through the pipe 17.

The condenser preferably consists of two vertically arranged coils located near each side of the pump casing 1 and interconnected at the top by means of a pipe 18 and at the bottom by means of a pipe 19. These coils are preferably provided with heat radiating fins which serve to increase the radiating surface. The fan 6 is preferably constructed so as to produce a diverging current of air, and inasmuch as the condenser coils are located near the sides of the casing 1, the air which comes in contact with the coils does not thereafter come in contact with the casing. It is desirable to have air at atmospheric temperature come in contact with the casing rather than air which has been heated by coming in contact with the condenser coils.

My improved pump casing 1 comprises a casting having an opening in the side thereof near the top covered by the closure plate 11 and having a second opening in the top of the casing covered by the closure plate 10. One or more tubular members 20 are provided in the casing near the bottom thereof and preferably integral with the casing. These members form air passages extending through the casing and arranged in such a manner that some of the air set in motion by the fan 6 passes through these members, thus cooling the contents of the casing. This cooling feature is provided primarily for the purpose of cooling the sealing fluid for the rotary pump, but it will be understood that the compressed gas within the casing is also cooled to some extent by the air passing through these tubular members.

The tubular members 20 within the casing 1 are preferably formed in such a manner that the diameter at some point intermediate the ends of each member is less than the diameters of the ends, thus providing a Venturi throat through which the air passes. This serves to cause the air to pass through at high velocity, and this increases the efficiency of the air as a cooling medium. To further increase the velocity of the air and to thoroughly mix the same, I may provide a plurality of spiral baffles 21 within each of the tubular members 20.

The motor 4 and compressor casing 1 are mounted on a suitable support or bed plate 22, and I prefer to mount the casing 1 in such a manner that it is spaced apart from the surface of the bed plate in order to permit the air to pass underneath the casing to cool the bottom of the same. In order to increase this cooling effect, I may provide a plurality of ribs 23 along the bottom of the casing. The tubular members 20 are

preferably spaced above the bottom of the inside of the casing, and the oil which collects in the bottom of the casing is cooled not only by the air passing through the members 20, but also by the air passing underneath the casing. A pipe 24 dips into the oil in the bottom of the casing 1 and serves to deliver the oil to the intake side of the rotary pump.

Any suitable pump can be used for the purpose of compressing the refrigerant, but I prefer to use a rotary pump such as that described in the Groh patent No. 1,495,411. I have found that where a pump of this type is employed, it is desirable to provide some means for preventing motor action of the pump. When the motor 4 stops, there is a tendency for the pump 2 to act as a motor and operate backwards due to the high pressure of the refrigerant within the casing 1. In order to prevent this action, the result of which would be to permit the compressed refrigerant to escape into the pipe 12, I prefer to provide a check valve such as that illustrated in detail in Fig. 4. This valve comprises a movable valve member 25, cooperating with a valve seat 26 and arranged so that under normal operation of the system, the partial vacuum created by the pump is sufficient to cause the refrigerant in the pipe 12 to lift the valve and permit the refrigerant to escape past the valve and into the pump. When the pump stops, however, the valve closes and prevents or limits motor action of the pump.

The pump 2 and the tubular members 20 are arranged within the casing 1 in such a manner that the sealing fluid discharged from the pump comes in contact with these members and the sealing fluid is thereby cooled. In order to compel the oil to come directly in contact with the members 20 instead of a portion of it flowing down the side of the casing 1, I prefer to provide one or more baffle or rib members 27, preferably integral with the casing and projecting in toward the center of the casing.

I have provided a pair of pet-cocks 28 and 29 on one side of the casing 1, which serve as a means for ascertaining the level of the sealing fluid within the casing. These pet-cocks are arranged at different levels and the casing is normally supplied with sufficient oil so that the level of this liquid is near the upper pet-cock. If at any time it is found that the level is not high enough so that the oil will flow out of the lower pet-cock, then oil can be supplied to the system until there is sufficient oil so that some of it will flow out of the upper pet-cock. These pet-cocks are of course closed during the normal operation of the system.

It is desirable to provide some means for filtering the compressed refrigerant before it leaves the casing 1, thus preventing small

globules or particles of oil from passing through the pipe 8 into the condenser 7. To accomplish this result, I have provided a screening device 30 consisting of a plurality 5 of concentrically arranged tubular screens and carried by the closure plate 10. The parts are preferably so arranged that this screening device is on the side of the pump remote from the point of discharge from the 10 pump.

The valve 9 carried by the closure plate 10 comprises a threaded valve member 31 having a double valve head cooperating with a valve seat 32 formed in the closure plate 10, 15 and with the threaded end of a plug 33 which carries the valve member. The plug 33 has a screw-threaded connection with the cover plate 10 and it is adapted to receive packing 34 held in place by a packing ring 20 35. The outer end of the valve member 31 is adapted to receive a wrench, and this end of the member is normally enclosed within the plug member 33 by a cap 36. The construction and arrangement of the valve is 25 such that during normal operation of the system, the valve head is closed against the end of the plug 33, thus preventing the refrigerant from passing along the screw-threads toward the packing 34. The valve 30 member can be moved to its other extreme position whenever it is necessary to prevent the refrigerant from flowing into the condenser 7.

Any suitable valve manifold can be used 35 for the purpose of supplying refrigerant and sealing fluid to the system or discharging the refrigerant and sealing fluid from the system, but I prefer to use a valve manifold of the type shown in the accompanying 40 drawings and described and claimed in my co-pending application, Serial No. 143,289 filed October 21, 1926. This valve manifold, indicated by the reference character 13, comprises a casting having lateral passages and 45 a transverse connection 37 interconnecting the lateral passages. A filling port is arranged in one side of the casting, preferably in line with the transverse connection 37, this port being normally closed by a plug 38. 50 Valves 39 and 40 control the communication between the port above mentioned and the two lateral passages extending through the manifold. Similar valves 40 and 41 control the flow of refrigerant through the valve 55 manifold, valve 40 being arranged to control the flow through pipe 12 and valve 41 controlling the flow through pipe 15.

Any suitable expansion valve may be employed, but I prefer to use an expansion 60 valve of the type illustrated in the accompanying drawings and described and claimed in my co-pending application, Serial No. 149, 844 filed November 22, 1926. This valve is of the float type and comprises a float chamber 65 communicating with the valve manifold 13

by means of the pipe 15. When the level of the liquid refrigerant in the float chamber rises to a certain point, the float valve opens to permit some of the refrigerant to escape into the pipe 17 leading to the refrigeration element. The liquid flows through pipe 17 and ultimately changes to the gaseous state within the refrigeration element. A pet-cock 42 may be provided near the top of the float chamber. This 70 serves as a means for withdrawing any air trapped in the system while it is being charged, and for withdrawing from the system any non-condensable gases which may be formed therein.

The float valve 16 and the valve manifold 13 are preferably arranged on opposite sides of the driving motor 4, and the fan 6 is preferably arranged between the motor and the pump casing 1, with the condenser coils arranged near the fan and near the sides of the pump casing 1. With the parts arranged in this manner, they are readily accessible for making repairs, and the apparatus can be assembled with the minimum of labor. The 80 apparatus occupies a very small space, thus making it particularly suitable for domestic refrigeration purposes. It is not necessary to have any cooling apparatus for the sealing fluid, arranged on the outside of the compressor casing, and the construction and arrangement of parts is such that the cooling air is used in a very efficient manner.

It is to be understood that the invention is not limited to the particular embodiment 100 illustrated and described, but includes such modifications thereof as fall within the scope of the appended claims.

I claim:

1. In a refrigerating apparatus, the combination of a casing adapted to hold oil and having an air conduit extending therethrough, means within the casing for compressing a gasified refrigerant, a condenser communicating with said casing and arranged in close proximity thereto, and means for causing air to flow through said conduit and to flow against the condenser.

2. In a refrigerating apparatus, the combination of a casing adapted to hold oil and having an air conduit extending therethrough, means within the casing for compressing a gasified refrigerant, a condenser comprising two interconnected units arranged near opposite sides of said casing, and 110 a fan for causing air to flow through said conduit and to flow against the condenser.

3. In a refrigerating apparatus, the combination of a casing adapted to hold oil and having an air conduit extending therethrough and arranged so that the oil may come in contact with at least two sides thereof, a pump within said casing for compressing a gasified refrigerant, a shaft connected to said pump, a motor connected to 125 130

said shaft, a condenser communicating with said casing and arranged near two sides thereof, and a fan mounted on said shaft for causing air to flow through said conduit and to flow against the condenser.

5 4. In a refrigerating apparatus, the combination of a casing adapted to hold oil and having an air passage extending therethrough, means within the casing for compressing a gasified refrigerant, a condenser communicating with said casing and arranged near two sides thereof, and a fan for causing air to flow through said passage and to flow against the condenser, the fan, condenser and casing being constructed and arranged so that the air coming in contact with the condenser does not thereafter come in contact with the casing or pass through the air passage therein.

10 5. In a refrigerating apparatus, the combination of a gas-tight casing adapted to hold oil and having an air passage extending therethrough, and a plurality of heat radiating ribs on the bottom thereof, a rotary pump within the casing for compressing a gasified refrigerant, means for operating the pump, a condenser communicating with the casing and arranged adjacent thereto, and means for causing air to flow against said condenser, through said passage and along said ribs on said casing to cool the oil in said casing.

15 6. In a refrigerating apparatus, the combination of a gas-tight casing, a rotary pump therein for compressing a gasified refrigerant, a condenser communicating with said casing and receiving the compressed refrigerant therefrom, sealing oil for the pump, means for operating the pump, a tubular member within the casing forming an air passage extending therethrough, and means for causing air to flow against said condenser and through said passage, the inner diameter of said member being smaller intermediate the ends thereof than the diameters of the ends of said member.

20 7. In a refrigerating apparatus, the combination of a gas-tight casing, a rotary pump therein for compressing a gasified refrigerant, a condenser including two connected spaced units communicating with said casing and receiving the refrigerant compressed by said pump, sealing oil for the pump, means for operating the pump, a tubular member within the casing forming an air passage extending therethrough, the axis of said pas-

sage passing between the two units of said condenser, and means for causing air to flow against said condenser and through said passage, the said member having spiral baffles on the interior walls thereof.

25 8. In a refrigerating apparatus, the combination of a gas-tight casing, a rotary pump therein for compressing a gasified refrigerant, a condenser adjacent said casing and communicating therewith for receiving the refrigerant compressed by said pump, a tubular member within the casing forming an air passage extending therethrough, and means for causing air to flow against said condenser and through said passage, the said member having spiral baffles on the interior thereof, and the inner diameter of said member being smaller intermediate the ends thereof than the diameters of the ends of said member.

30 9. In a refrigerating apparatus, the combination of a gas-tight casing, a rotary pump therein for compressing a gasified refrigerant, a condenser communicating with said casing and arranged in close proximity thereto, sealing oil for the pump, means for operating the pump, a tubular member within the casing forming an air passage extending therethrough, and means for causing air to flow against said condenser and through said passage, the said member being arranged near the bottom of the casing but spaced apart therefrom, and the bottom of the casing being provided with a plurality of heat radiating ribs.

35 10. In a refrigerating apparatus, a gas-tight casing adapted to hold sealing oil and having an opening in one side thereof near the top of the casing, a tubular member integral with the casing forming an air passage extending therethrough, a detachable closure plate for the opening in said casing, a rotary pump supported by said closure plate, the said pump being arranged with respect to said tubular member in such a manner that sealing oil discharged from the pump comes in contact with said member, a condenser comprising two spaced interconnected coils communicating with said casing, said coils being located on opposite sides of the axis of said tubular member, and means for causing air to flow against said condenser and through said tubular member.

40 In testimony whereof I affix my signature

ALFRED M. THOMSON
